[57] **CLAIM**

An ornamental design for combined container and
valve closure, as shown and described.

DESCRIPTION

FIG. 1 is a top front perspective view of a combined
container and valve closure showing my new design;
FIG. 2 is a bottom and front perspective view thereof;
FIG. 3 is a front elevation thereof, the rear elevation is
the same;

FIG. 4 is a side elevation thereof, the opposite side is the
same;

FIG. 5 is a top plan view thereof with the valve slide in
a closed position;

FIG. 6 is a top plan view thereof with valve slide in an
open position; and,

FIG. 7 is a bottom plan view thereof.

FIG. 1

FIG. 2
